UNITED STATES PATENT OFFICE.

WILLIAM H. COOLEY, OF BROCKPORT, NEW YORK.

LOOSE-LEAF BINDER AND LEAF THEREFOR.

1,044,753.

Specification of Letters Patent. Patented Nov. 19, 1912.

Application filed May 6, 1911, Serial No. 625,573. Renewed April 4, 1912. Serial No. 688,531.

To all whom it may concern:

Be it known that I, WILLIAM H. COOLEY, a citizen of the United States, and a resident of Brockport, in the county of Monroe and State of New York, have invented a new and useful Improvement in Loose-Leaf Binders and Leaves Therefor, of which the following is a specification.

This invention relates to loose leaf binders of the expansion type in which cover members are hinged to two relatively movable members each carrying impaling posts with the impaling posts carried by one of such plates adapted to telescope with the correspondingly positioned posts carried by the other plate.

Essential features of my invention, however, are equally applicable to all loose leaf binders of that class in which there are provided a plurality of pairs of oppositely disposed impaling members arranged in two relatively movable and opposite series with the oppositely disposed impaling members of each pair adapted to engage into the one correspondingly positioned opening therefor in the leaves adapted to use in the binder, although, in the accompanying drawings, I have shown my invention as applied only to a loose leaf binder of the expansion type.

I have found in the use of such binders in the removal and insertion of leaves that they frequently get misplaced and inserted wrong side up resulting in confusion and inconvenience which it is the purpose of my present invention to overcome. This result I accomplish by so locating the impaling posts in the binder and the corresponding openings therefor in the leaves that such leaves may preferably, although not necessarily, be insertable in the binder with only one side thereof uppermost, while however, such an arrangement of the impaling posts and the openings in the leaves therefor may be made in accordance with my invention as to prevent the insertion of the leaves in alinement in the binder with only one side thereof uppermost although in the drawings I have shown the former modification in which it is impossible to insert the leaves in the binder except with one side thereof uppermost.

The accompanying drawings illustrating a loose leaf binder of well known construction and leaves therefor embodying my invention are as follows,—

Figure 1 is a perspective view of the binder with leaves therein and with the binder partially opened and one cover leaf in opened position. Fig. 2 is a plan view of a part of one of the leaves. Fig. 3 is a diagrammatic elevation of the arrangement of the posts and part of the plates or sides of the binder for carrying the same.

Similar parts are designated by similar reference characters throughout the several figures of the drawings.

Referring to the drawings, B and C are the cover members each hinged to the corresponding portion D and D¹ of the binder frame carrying the plates P and P¹ respectively and preferably integrally formed therewith in which are secured the telescoping impaling posts p and p¹ and n and n¹ and n² and n³ and p² and p³ respectively and, inasmuch as the binders of this class are not designed to be opened far enough to separate the telescoping impaling posts carried by the opposite plates from each other, the leaves for insertion in such a binder are provided with open slotted holes such as seen at e, e¹, e² and e³ to permit such leaves to be inserted in the binder in the usual way. It will be noticed, however, that the centers of the posts p and n and their co-operating members n² and p² are spaced a lesser distance apart than the posts p¹ and n¹ and the co-operating members n³ and p³. It will also be noticed that the post p and the co-operating member n² are placed nearer the left hand ends of the plates P and P¹ respectively than the posts n¹ and the co-operating member p³ from the right hand end, of the plates P and P¹. In a similar way also the post n and the co-operating member p² are placed a lesser distance from the left hand ends of the plates P and P¹ respectively than the posts p¹ and the co-operating member n³ from the right hand ends of such plates. The result of this arrangement of the posts is such that leaves having openings correspondingly positioned to receive such posts can be inserted in the binder with only one side thereof upper-

most. It will also be seen at once that in a pile of such leaves, when removed from or before insertion in the binder, any leaf placed wrong side up is readily detected by 5 the lack of alinement in the series of openings e, e^1, e^2 and e^3 . Any such leaf or leaves may be readily removed from the pile and placed right side up. The leaves of course are inserted in such a binder in the usual 10 way and are clamped by closing the binder in the usual way. The side members D and D^1 are actuated to and from each other by means of a key engaging the end of the operating rod r toward the observer.

15 From the foregoing description of the above indicated embodiment thereof it is believed, that my invention and the application and method of using the same is sufficiently clear to call for no further explanation herein.

20 It is of course understood that there must be such coöperation as to the conformation of the impaling members and the openings in the leaves therefor as to secure and maintain alinement of the leaves in the binder.

25 It will of course be understood that at least three impaling members are required in order that they may be placed in such unsymmetrical relation as to prevent the insertion thereover of a leaf having corresponding and correspondingly positioned openings therein, except with only one side of the leaf uppermost.

What I claim is:

30 1. In a loose leaf binder, two relatively movable side members each carrying at least three impaling members each coöoperating with the corresponding impaling member on the other side member to engage within the 35 one correspondingly positioned opening therefor in leaves adapted to use in the binder, the impaling members unsymmetrically disposed, whereby a leaf having corresponding and correspondingly positioned 40 openings therein may be inserted over the impaling members with only one side thereof uppermost.

45 2. In a loose leaf binder, two relatively movable side members each carrying at least three impaling members each coöoperating with the corresponding impaling member on the other side member to engage within the one correspondingly positioned opening therefor in leaves adapted to use in the 50 binder, the two outer pairs of coöoperating and corresponding impaling members disposed at unequal distances from the opposite edges of the leaves adjacent to their back edges, whereby a leaf having corresponding 55 and correspondingly positioned openings therein may be inserted over the impaling members with only one side thereof uppermost.

60 3. In a loose leaf binder, two relatively movable side members each carrying at least

65 fear impaling members each coöoperating with the corresponding impaling member on the other side member to engage within the one correspondingly positioned opening therefor in leaves adapted to use in the 70 binder, the two inner pairs of coöoperating and corresponding impaling members disposed at unequal distances from the opposite edges of the leaves adjacent to their back edges, whereby a leaf having corresponding 75 and correspondingly positioned openings therein may be inserted over the impaling members with only one side thereof uppermost.

4. In a loose leaf binder, two relatively 80 movable side members each carrying at least four impaling members each coöoperating with the corresponding impaling member on the other side member to engage within the one correspondingly positioned opening 85 therefor in leaves adapted to use in the binder, the two inner pairs of coöoperating and corresponding impaling members disposed at unequal distances from a central point between the two outer pairs of coöperating and corresponding impaling members, whereby a leaf having corresponding 90 and correspondingly positioned openings therein may be inserted over the impaling members with only one side thereof uppermost.

95 5. In a loose leaf binder, two relatively movable side members each carrying at least three impaling members each coöoperating with the corresponding impaling member on 100 the other side member to engage within the one correspondingly positioned opening therefor in leaves adapted to use in the binder, one pair of such coöoperating and corresponding impaling members disposed 105 at unequal distances from adjacent pairs of coöperating and corresponding impaling members on opposite sides thereof whereby a leaf having corresponding and correspondingly positioned openings therein may be 110 inserted over the impaling members with only one side thereof uppermost.

115 6. In a loose leaf binder, two relatively movable side members each carrying at least three impaling members each coöoperating with the corresponding impaling member on the other side member to engage within the one correspondingly positioned opening therefor in leaves adapted to use in the binder, the impaling members unsymmetrically disposed, and leaves having corresponding and correspondingly positioned 120 openings therein and adapted to be inserted over the impaling members with only one and the same and corresponding side of each 125 one thereof uppermost.

130 7. In a loose leaf binder, two relatively movable side members each carrying at least three impaling members each coöoperating with the corresponding impaling member on

the other side member to engage within the one correspondingly positioned opening therefor in leaves adapted to use in the binder, the two outer pairs of coöperating and corresponding impaling members disposed at unequal distances from the opposite edges of the leaves adjacent to their back edges and leaves having corresponding and correspondingly positioned openings therein and adapted to be inserted over the impaling members with only one and the same and corresponding side of each one thereof uppermost.

8. In a loose leaf binder, two relatively movable side members each carrying at least four impaling members each coöperating with the corresponding impaling member on the other side member to engage within the one correspondingly positioned opening therefor in leaves adapted to use in the binder, the two inner pairs of coöperating and corresponding impaling members disposed at unequal distances from the opposite edges of the leaves adjacent to their back edges and leaves having corresponding and correspondingly positioned openings therein and adapted to be inserted over the impaling members with only one and the same and corresponding side of each one thereof uppermost.

9. In a loose leaf binder, two relatively movable side members each carrying at least four impaling members each coöperating with the corresponding impaling member on the other side member to engage within the one correspondingly positioned opening therefor in leaves adapted to use in the binder, the two inner pairs of coöperating and corresponding impaling members disposed at unequal distances from a central point between the two outer pairs of coöperating and corresponding impaling members and leaves having corresponding and correspondingly positioned openings therein and adapted to be inserted over the impaling members with only one and the same and corresponding side of each one thereof uppermost.

10. In a loose leaf binder, two relatively movable side members each carrying at least three impaling members each coöperating with the corresponding impaling member on the other side member to engage within the one correspondingly positioned opening therefor in leaves adapted to use in the binder, one pair of such coöperating and corresponding impaling members disposed at unequal distances from adjacent pairs of coöperating and corresponding impaling members on opposite sides thereof and leaves having corresponding and correspondingly positioned openings therein and adapted to be inserted over the impaling members with only one and the same and corresponding side of each one thereof uppermost.

11. In a loose leaf binder, two relatively movable side members each carrying at least three impaling members each coöperating with the corresponding impaling member on the other side member to engage within the one correspondingly positioned opening therefor in leaves adapted to use in the binder, the impaling members disposed unsymmetrically but in alinement whereby a leaf having corresponding and correspondingly positioned openings therein may be inserted over the impaling members with only one side thereof uppermost. 70

12. In a loose leaf binder, two relatively movable side members each carrying at least three impaling members each coöperating with the corresponding impaling member on the other side member to engage within the one correspondingly positioned opening therefor in leaves adapted to use in the binder, the impaling members disposed in alinement and the two outer pairs of coöperating and corresponding impaling members disposed at unequal distances from the opposite edges of the leaves adjacent to their back edges, whereby a leaf having corresponding and correspondingly positioned openings therein may be inserted over the impaling members with only one side thereof uppermost. 80

13. In a loose leaf binder, two relatively movable side members each carrying at least four impaling members each coöperating with the corresponding impaling member on the other side member to engage within the one correspondingly positioned opening therefor in leaves adapted to use in the binder, the impaling members disposed in alinement and the two inner pairs of coöperating and corresponding impaling members disposed at unequal distances from the opposite edges of the leaves adjacent to their back edges, whereby a leaf having corresponding and correspondingly positioned openings therein may be inserted over the impaling members with only one side thereof uppermost. 95

14. In a loose leaf binder, two relatively movable side members each carrying at least four impaling members each coöperating with the corresponding impaling member on the other side member to engage within the one correspondingly positioned opening therefor in leaves adapted to use in the binder, the impaling members disposed in alinement and the two inner pairs of coöperating and corresponding impaling members disposed at unequal distances from a central point between the two outer pairs of coöperating and corresponding impaling members, whereby a leaf having corresponding and correspondingly positioned openings therein may be inserted over the impaling members with only one side thereof uppermost. 110

15. In a loose leaf binder, two relatively movable side members each carrying at least three impaling members each coöperating with the corresponding impaling member on the other side member to engage within the one correspondingly positioned opening therefor in leaves adapted to use in the binder, the impaling members disposed in alinement and one pair of such coöperating and corresponding impaling members disposed at unequal distances from adjacent pairs of coöperating and corresponding impaling members on opposite sides thereof, whereby a leaf having corresponding and correspondingly positioned openings therein may be inserted over the impaling members with only one side thereof uppermost.
16. In a loose leaf binder, two relatively movable side members each carrying at least three impaling members each coöperating with the corresponding impaling member on the other side member to engage within the one correspondingly positioned opening therefor in leaves adapted to use in the binder, the impaling members disposed unsymmetrically but in alinement, and leaves having corresponding and correspondingly positioned openings therein and adapted to be inserted over the impaling members with only one and the same and corresponding side of each one thereof uppermost.
17. In a loose leaf binder, two relatively movable side members each carrying at least three impaling members each coöperating with the corresponding impaling member on the other side member to engage within the one correspondingly positioned opening therefor in leaves adapted to use in the binder the impaling members disposed in alinement and the two outer pairs of coöperating and corresponding impaling members disposed at unequal distances from the opposite edges of the leaves adjacent to their back edges and leaves having corresponding and correspondingly positioned openings therein and adapted to be inserted over the impaling members with only one and the same and corresponding side of each one thereof uppermost.
18. In a loose leaf binder, two relatively movable side members each carrying at least four impaling members each coöperating with the corresponding impaling member on the other side member to engage within the one correspondingly positioned opening therefor in leaves adapted to use in the binder the impaling members disposed in alinement and the two inner pairs of coöperating and corresponding impaling members disposed at unequal distances from the opposite edges of the leaves adjacent to their back edges and leaves having corresponding and correspondingly positioned openings therein and adapted to be inserted over the impaling members with only one side thereof uppermost.
19. In a loose leaf binder, two relatively movable side members each carrying at least four impaling members each coöperating with the corresponding impaling member on the other side member to engage within the one correspondingly positioned opening therefor in leaves adapted to use in the binder, the impaling members disposed in alinement and the two inner pairs of coöperating and corresponding impaling members disposed at unequal distances from a central point between the two outer pairs of coöperating and corresponding impaling members and leaves having corresponding and correspondingly positioned openings therein and adapted to be inserted over the impaling members with only one and the same and corresponding side of each one thereof uppermost.
20. In a loose leaf binder, two relatively movable side members each carrying at least three impaling members each coöperating with the corresponding impaling member on the other side member to engage within the one correspondingly positioned opening therefor in leaves adapted to use in the binder, the impaling members disposed in alinement and one pair of such coöperating and corresponding impaling members disposed at unequal distances from adjacent pairs of coöperating and corresponding impaling members on opposite sides thereof and leaves having openings therein correspondingly positioned to receive the impaling members and adapted to be inserted over the impaling members with only one and the same and corresponding side of each one thereof uppermost.
21. In a loose leaf binder at least three pairs of oppositely disposed impaling members arranged in two relatively movable and opposite series with the oppositely disposed impaling members of each pair adapted to engage into the one correspondingly positioned opening therefor in the leaves adapted to use in the binder, such pairs of impaling members unsymmetrically disposed, whereby a leaf having corresponding and correspondingly positioned openings therein may be inserted over the impaling members with only one side thereof uppermost.
22. In a loose leaf binder at least three pairs of oppositely disposed impaling members arranged in two relatively movable and opposite series with the oppositely disposed impaling members of each pair adapted to engage into the one correspondingly positioned opening therefor in the leaves adapted to use in the binder, such pairs of impaling members unsymmetrically disposed and leaves having corresponding and corre-

spondingly positioned openings therein and adapted to be inserted over the impaling members with only one and the same and corresponding side of each one thereof uppermost.

23. In a loose leaf binder at least three pairs of oppositely disposed impaling members arranged in two relatively movable and opposite series with the oppositely disposed impaling members of each pair adapted to engage into the one correspondingly positioned opening therefor in the leaves adapted to use in the binder, such pairs of impaling members disposed unsymmetrically but in alinement, whereby a leaf having corresponding and correspondingly positioned openings therein may be inserted over the impaling members with only one side thereof uppermost.

24. In a loose leaf binder at least three pairs of oppositely disposed impaling members arranged in two relatively movable and opposite series with the oppositely disposed impaling members of each pair adapted to engage into the one correspondingly positioned opening therefor in the leaves adapted to use in the binder, such pairs of impaling members disposed unsymmetrically but in alinement and leaves having corresponding and correspondingly positioned openings therein and adapted to be inserted over the impaling members with only one and the same and corresponding side of each one thereof uppermost.

25. A leaf for a loose leaf binder having at least three openings therein to receive impaling members disposed in alinement but unsymmetrically whereby such leaf is insertible over corresponding and correspondingly positioned impaling members with only one side thereof uppermost.

26. A leaf for a loose leaf binder having four openings therein to receive impaling members disposed in alinement but unsymmetrically whereby such leaf is insertible over corresponding and correspondingly po-

sitioned impaling members with only one side thereof uppermost.

27. A leaf for a loose leaf binder having four openings therein to receive impaling members disposed in alinement but unsymmetrically, the two outer openings disposed at unequal distances from the opposite edges of the leaf adjacent to the back edge whereby such leaf is insertible over corresponding and correspondingly positioned impaling members with only one side thereof uppermost.

28. A leaf for a loose leaf binder having four openings therein to receive impaling members disposed in alinement but unsymmetrically, the two inner openings disposed at unequal distances from the opposite edges of the leaf adjacent to the back edge whereby such leaf is insertible over corresponding and correspondingly positioned impaling members with only one side thereof uppermost.

29. A leaf for a loose leaf binder having four openings therein to receive impaling members disposed in alinement but unsymmetrically, the two inner openings disposed at unequal distances from a central point between the two outer openings whereby such leaf is insertible over corresponding and correspondingly positioned impaling members with only one side thereof uppermost.

30. A leaf for a loose leaf binder having four openings therein to receive impaling members disposed in alinement but unsymmetrically, one of such openings disposed at unequal distances from an adjacent opening on either side thereof whereby such leaf is insertible over corresponding and correspondingly positioned impaling members with only one side thereof uppermost.
